LUCIO LOPEZ-MANTARAS, OF MADRID, SPAIN, ASSIGNOR OF ONE-HALF TO SOCIEDAD ANONIMA ERA, OF MADRID, SPAIN, A SOCIETY OF SPAIN

ADAPTATION OF DIFFERENT MUSICAL INSTRUMENTS BEING PLAYED WITH PIANOLAS SIMULTANEOUSLY

Application filed February 1, 1927, Serial No. 165,174, and in Spain July 5, 1926.

This invention relates to improvements in automatic musical instruments of the pneumatically operated type in which means are provided for enabling additional musical instruments to be played simultaneously with said first-named musical instruments.

Various types of automatic musical instruments are known which can be used to play the piano with an organ or any other musical instruments simultaneously; however in all of them the adaptation of the extra instruments to the automatic musical instrument is complicated and expensive, and must of necessity be carried out by the maker of the automatic instrument or by persons closely conversant with the mechanism.

It has already been proposed to employ a construction whereby a number of percussive instruments (drum, triangle, cymbal, castanets) may be played automatically and simultaneously with a pneumatically operated automatic piano. In such construction it was proposed to utilize the same tracker bar with the holes controlling the auxiliary instruments displaced if desired. From these holes tubes were led in a conduit to a connecting socket on the assembly of auxiliary instruments, and thence to the diaphragms and valves operating the striking pneumatics of the auxiliary instruments.

The object of the present invention is to render possible the application of one or several additional instruments to any pneumatically operated automatic piano whatsoever which can be played by any one in a simple and expeditious way without affecting the mechanism of the automatic piano, and also to render it possible in the same way to uncouple said instruments, leaving the automatic piano exactly as it was before.

The invention consists in a device for adapting additional musical instruments to be played simultaneously with a pneumatically operated automatic piano, comprising an additional detachable tracker bar co-operating with an additional set of note perforations on the music sheet, an additional suction system including an additional blower co-operating with the additional tracker bar, a branch pipe connecting said additional suc-

tion system to the main suction system of the piano, and a connecting member for the pipes coming from the additional tracker bar, which member is provided with bleed orifices, all the additional members forming with the auxiliary instruments a complete unit separate from the automatic piano and constituting a mechanism which is to be coupled to the automatic piano when the additional instruments comprised therein are to be played.

The invention is illustrated in the accompanying drawings, in which:

Figure 1 is a front view of the auxiliary apparatus with several instruments adapted to an automatic piano;

Figure 2 shows a front view of said apparatus;

Figure 3 is a side view of Figure 2;

Figure 4 is a detail view of the additional tracker bar and a part of the roll, showing the two sections into which it is divided;

Figure 5 shows a section of Figure 4 through the additional tracker bar;

Figure 6 is a combined elevation, the upper portion showing the inner face of one air release member, and the lower portion the inner face of the associated member;

Figure 7 is a central, horizontal section of the assembled members;

Figure 8 is a similar view at a right angle to Figure 7;

Figure 9 is a section through the body of the drum which forms one of the additional instruments, and

Figure 10 shows, by way of example, a constructional form of a valve and bellows or pneumatic from which the particular disposition of an air release orifice or bleed can be seen.

Figure 1 shows an ordinary automatic piano, and indicates by dotted lines the boxes containing the automatic mechanism similar to that of such pianos, the upper box A being the valve box and the lower box B containing the blowing pneumatics. The piano is provided with the normal tracker bar O', having apertures Y', supported beneath the partition T', and having pneumatic connections R' and S' of the usual character.

In the tube C uniting these two boxes a

branch is established by means of a T piece D and the flexible tube E, whereby the auxiliary apparatus may be operated from the pneumatic blowing system of the automatic piano, or whereby, on the other hand, the suction device of the auxiliary apparatus may operate the piano. On the auxiliary apparatus are also indicated in dotted lines its valve box F and in full lines the tubes E, H, I, that establish the communication from the boxes A and B of the piano to the apparatus F and the suction apparatus J. This suction apparatus J is constituted by a set of bellows operated by an electric motor K or by any other motor, and produces a vacuum sufficient for the working of the auxiliary apparatus and the piano if desired. On moving the pedals of the piano, the latter will start playing and through the medium of the tubes D, E, H, the vacuum will be caused to operate on the valve box F of the apparatus, in which there will always be the same pressure as in the box A of the piano.

If the motor K is started up, the suction apparatus J will produce a vacuum which will be communicated through the medium of the tubes I, E, D, to the boxes A, B, of the piano, and through I, H, to the box F of the instrument, and will thus cause both to function simultaneously. The two playing operations are independent of one another and can take place at the same time in order to strengthen the sound. Figure 1 shows also the location of the additional tracker bar Q' which is shown in detail in Figures 4 and 5, and the connecting conduit L which consists of a tube that contains others of less diameter, and in fact as many as there are valves or pneumatics on the second instrument.

This conduit L can pass between the top of the piano and the side when its installment is temporary. Both the said conduit and the suction tube E can, if desired, be permanently fixed by attachment to the wall of the piano. The tube O serves to actuate an automatic interrupter P, when the end of the roll is reached, if an electric motor is used. If the tube E which connects the second instrument with the vacuum boxes of the piano is shut off, it will only be necessary to put the supplementary tracker bar in position in order to enable the apparatus to operate completely independently of the piano, the vacuum being in this case adjusted accordingly on the suction apparatus J.

The coupled instrument shown in Figure 2 is constituted by several orchestral instruments which are similar to the instruments used in the so-called jazz-band and the particular disposition of which can be seen in the said drawing.

The body of the drum 1 contains the complete pneumatic mechanism of the apparatus constituted by a box of valves and as many actuating pneumatics as the instrument has

hammers or strikers, together with one extra pneumatic which acts on the lever 2 of the dampers, these latter acting on the cymbal 3 and the drum and on the tambour 6 or side drum. The pneumatic mechanism may also contain one or several bellows adapted in known manner to vary the distance or strength of percussion of the hammers. 70

The instruments constituting the mechanism are: The drum 1, the tambour 6, the cymbal 3, the triangle 8, and a tablet of tap box 7 with two hammers 9; 10 is the striker of the drum; 11 are the drum sticks for the side drum; 12 is the striker of the triangle; 13 that of the cymbal; 14 is a supporting piece serving to fix the cymbal to the rim of the drum; 15 is a stop member which prevents excessive movement of the triangle; 16 is a nut for adjusting the height of the triangle; 17 are the supporting pieces of the drum sticks of the tambour or side drum, and 18 are the tension screws of the side drum and 19 the tension screws of known type for the bass drum. 75 80 85

In Figure 3 the same parts as in Figure 2 are shown from the side; 20 and 21 are the members which constitute the support or pedestal of the apparatus.

Figure 4 is a view of the additional tracker bar and its position in an automatic piano. The principal part is the piece L'' formed by a small plate provided with as many holes V' as there are pneumatics on the accessory instrument. Its form is such, that the perforated roll of paper is perfectly adapted to its surface as well as to that of the tracker bar of the piano. The member M' is a celluloid film or other flexible resistant member which is adapted to fit the tracker bar of the piano accurately, covering as many holes of this as the additional tracker bar has, with the object of preventing the piano from playing the notes corresponding to the sounds of the accessory instruments. This cut-off M' is mounted on a pivot N' which permits of its being upwardly rotated in such manner as to uncover the openings in the piano and to cover those of the additional tracker bar, so that all the ordinary rolls can be played with all the notes of the piano operative. The additional tracker bar is maintained in its place by means of a bar which has on one of its ends a piece B' which by means of the nut C' can be displaced on the bar A' so as to vary the length formed by the said bar A' and the piece B' and thus adapt it to the piano, no matter what the distance may be between the partition walls of the roll-carrier apparatus. 100 105 110 115 120

On the other end of the bar A', there is a piece E' to which is fastened the plate of the additional tracker bar by means of the bridge F'; this piece E' being displaceable on the bar by means of the nut D', so that the apertures V' of the additional tracker bar can 125 130

be made to coincide exactly with the perforations of the music roll. The spring G maintains the piece E' resting against the nut D'.

The bar A' also carries on its end two pieces 5 H' which rest on the supporting pins I' of the music roll J', thus retaining the additional tracker bar in a convenient working position. The small tubes corresponding to the holes of the additional tracker bar are 10 enclosed in a common protecting conduit L passing through the case of the piano. It is only necessary to loosen the nut C' a little, in order to free the whole combination of the 15 additional tracker bar so that it can be separated from the automatic piano, thus leaving the latter in its normal condition. Figure 5 is a vertical section of Figure 4 showing some of the details more clearly.

In Figure 4 it may also be observed that the 20 distance existing between the holes V' of the additional tracker bar and the apertures Y' of the piano is exactly equal to the distance o'' maintained between two lines of notes x' and x one of the piano and the other of the 25 accessory instrument which notes are both to be sounded simultaneously. This distance remains constant in the perforation of the two sections of the roll, viz section A'' for the 30 notes of the piano and section B'' for those of the instruments.

Figures 6, 7, 8, and 9 represent the device 35 which renders it possible to separate and unite again with facility the suction tubes of the pneumatic valves of the instrument and at the same time permit access to the small air release or bleed orifices, without the necessity 40 of dismounting any part of the instrument.

The general disposition may be seen from Figure 9, representing a section of the principal parts of the second instrument with the 45 valve box open.

The device proper is formed by the three 50 members a, b and c—a is a member to which the tubes leading from the automatic piano 55 to the said second instrument are joined, b is a thin metallic member lined with a membrane which assures perfect closure by the two surfaces when the three members are united in any known manner by the application 60 of slight external pressure, c is a small member similar to a which is permanently connected to the second instrument and receives the ends of the tubes s of the valves 65 coming from the interior of the second instrument.

The intermediate member b (Figure 8) has as many conduits d (Figure 6) passing 70 through it as the instrument has valves and also other smaller holes e that constitute the air release or bleed orifices of said valves. These small holes communicate on one side 75 with grooves f (Figure 7) formed in the body of the member a and on the other side with a groove h in the member c. This groove is in 80 communication with the vacuum box or body

i through the medium of the tube j, Figure 9; in this way the communication between the valve conduits d and the vacuum box through the grooves f, the apertures e and the groove h, Figure 10, remains established.

The said Figure 10 shows a constructional form of valve and striking bellows or pneumatic in which the position and the size of the pieces have been drawn somewhat out of proportion for greater clearness; k is any one 75 of the pneumatics that work the instrument; l is the valve that, putting the pneumatic in communication by m with the exterior or by n with the vacuum box i sets in action said pneumatic. The valve l is operated by the 80 elastic membrane o that separates the vacuum box i from the recess p. This recess is in communication with the corresponding hole of the additional tracker bar through the tube d; and when the hole of the additional 85 tracker bar is uncovered by the passage of a perforation in the music roll, the membrane o acts on the valve l. When once the perforation has passed and the holes of the tracker bar are covered again, the membrane o returns to its original position with regard to the recess p owing to the action of the small 90 air release orifice e which communicates with the vacuum box.

In order that the change of pressure before 95 mentioned in the interior of the recess p be sufficiently rapid for the proper working of the valve, it is necessary that the size of the orifice e should be very accurately adjusted with regard to that of the tracker bar. The 100 said orifice e being very small, must therefore always be kept perfectly clean. The above described device renders it possible to gain access readily to the member c for the purpose of cleaning the orifice e or of renewing said 105 member.

What is claimed is:—

1. A supplementary playing instrument 110 adapted to cooperate with the note sheet and normal tracker bar of a pneumatically operated piano, including an additional musical instrument having an actuating member, a pneumatic control for said member, and an additional tracker bar communicating with said control and cooperating with the note 115 sheet of the piano.

2. A supplementary playing instrument 120 adapted to cooperate with the note sheet and normal tracker bar of a pneumatically operated piano, including an additional musical instrument having an actuating member, a pneumatic control for said member, an additional tracker bar communicating with said control and cooperating with the note sheet 125 of the piano, and means to cut off from the note sheet either the additional tracker bar or the aligned portion of the normal tracker bar.

3. A supplementary playing instrument 130 adapted to cooperate with the note sheet and

normal tracker bar of a pneumatically operated piano, including an additional musical instrument having an actuating member, a pneumatic control for said member, an additional tracker bar communicating with said control and cooperating with the note sheet of the piano, and a pivoted cut off adapted to cover either the apertures of the additional tracker bar or the aligned apertures of the normal tracker bar.

4. A supplementary playing instrument adapted to cooperate with the note sheet and normal tracker bar of a pneumatically operated piano, including an additional musical instrument having an actuating member, a pneumatic control for said member, an additional tracker bar communicating with said control and cooperating with the note sheet of the piano, a motor pump for said pneumatic control, and connections from said pump to the normal and additional tracker bars.

5. A supplementary playing instrument adapted to cooperate with the note sheet and normal tracker bar of a pneumatically operated piano, including an additional musical instrument having an actuating member, a pneumatic control for said member, an additional tracker bar communicating with said control and cooperating with the note sheet of the piano, and an air release intermediate the additional tracker bar and the coupled instrument.

6. A supplementary playing instrument adapted to cooperate with the note sheet and normal tracker bar of a pneumatically operated piano, including an additional musical instrument having an actuating member, a pneumatic control for said member, an additional tracker bar communicating with said control and cooperating with the note sheet of the piano, and an air release intermediate the additional tracker bar and the coupled instrument comprising opposite recessed members enclosing a plate having bleed openings communicating with the additional tracker bar and the coupled instrument.

7. A supplementary playing instrument adapted to cooperate with the note sheet and normal tracker bar of a pneumatically operated piano, including an additional musical instrument having an actuating member, a pneumatic control for said member, and an additional tracker bar disposed to cooperate with a portion of the note sheet of the piano while the remainder thereof controls the piano action.

8. A supplementary playing instrument adapted to cooperate with the note sheet and normal tracker bar of a pneumatically operated piano, including an additional musical instrument having an actuating member, a pneumatic control for said member, an additional tracker bar communicating with said control and cooperating with the note sheet

of the piano, means to cut off from the note sheet either the additional tracker bar or the aligned portion of the normal tracker bar, a motor pump for said pneumatic control, connection from said pump to the normal and additional tracker bars, and an air release intermediate the additional tracker bar and the coupled instrument.

9. A device for adapting additional musical instruments to be played simultaneously with a pneumatically operated automatic piano comprising an additional detachable tracker bar cooperating with a set of note perforations on the music sheet for the piano, an additional pneumatic system cooperating with the additional tracker bar, a conduit connecting said system to the pneumatic system of the piano, a connecting conduit from the additional tracker bar to the additional musical instrument, and an air release in the last-named conduit provided with bleed openings.

In testimony whereof he affixes his signature.
